DEPOSIT ELIMINATOR

Joseph Audette, Burlington, Vt.

Application August 14, 1935, Serial No. 36,223

4 Claims. (Cl. 126—312)

This invention relates to deposit eliminators, and is a continuation in part of my application, Serial No. 727,162, filed May 23, 1934.

A primary object of the present invention is to construct and design a portion of a conductor pipe leading from a stove or heater to the chimney in the building so as to prevent the condensation of heavy products of combustion and eliminate their deposit in the conductor pipe. Further objects of the invention are to provide a device of the character referred to that is strong, compact and durable, thoroughly reliable for its intended purpose, adaptable for installation in any conductor pipe and easily installed therein, and that is comparatively inexpensive to manufacture.

Another feature of the present invention consists of a retarded draft without the products of combustion collecting in the conductor pipe thereby allowing the utilization of the maximum amount of heat in the stove and at the same time preventing the loss of heat escaping into the chimney.

With the foregoing and other objects in view, the invention consists of a novel construction, combination and arrangement of parts, as will be hereinafter more specifically described and illustrated in the accompanying drawings, wherein is disclosed an embodiment of the invention, but it is to be understood that changes, variations, and modifications may be resorted to without departing from the spirit of the claims hereunto appended.

In the drawings, wherein like reference numerals denote corresponding parts—

Figure 1 is a fragmentary portion of a stove and chimney showing an adaptation therewith of a conductor pipe embodying the features of the present invention.

Figure 2 is an axial detailed sectional view of a portion or section of the conductor pipe constructed in accordance with the present invention.

Figure 3 is a diametric section taken substantially on line 3—3 of Figure 2 and looking downwardly.

Figure 4 is a diametric section taken substantially on the plane of line 4—4 of Figure 2 and looking downwardly.

Figure 5 is a section similar to Figure 3 of the drawings showing a modified form of the damper for use in wood and soft coal burning stoves.

Referring to the drawings in detail, A indicates a conventional stove and B indicates a chimney in the building where the stove is located. The

conductor pipe C is connected at its lower end with the stove and at its other end with the chimney whereby the products of combustion are conveyed thereby from the stove to the chimney. The diameter of the conductor pipe is selected as desired.

As is customary in the trade, the conductor pipe C is formed of sections of standard lengths and these sections fit one into the other to form the continuous conductor pipe. Although the present invention will operate equally well when constructed in any portion or section of the conductor pipe C, I prefer to form the section of pipe indicated at 6 with the present invention, which section is that portion of the conductor pipe next to the stove. The section of conductor pipe 6 is round and preferably formed of sheet metal. A longitudinally extending partition wall 7 extends across the interior of the pipe section 6. The side edges of the partition wall 7 are formed with flanges which are bolted as at 8 to the wall of the pipe section 6. The partition wall extends from the upper end of pipe section 6 longitudinally thereof to a point near the lower end thereof where said partition wall is formed with a horizontal extension 9. The partition wall forms an air chamber 10 and the passage 11, through the latter of which the products of combustion pass on their way to the chimney. The air chamber 10 is segmental in horizontal cross section and materially less in area than the semi-circular cross section of the pipe section 6. The passage 11 for the products of combustion is materially greater in cross sectional area than the air chamber 10. It will be understood that the upper portion of pipe section 6, as shown in Figure 2 of the drawings, fits into the section of conductor pipe above it.

The lower end of chamber 10, that is, the end of the chamber next to the stove, is closed by the horizontal extension 9, and therefore the products of combustion from the stove cannot enter the lower end of the chamber 10. The upper end of the chamber 10 is open as at 12 and through this open end the chamber 10 communicates with the conductor pipe above the section 6. The pipe section 6 is formed with one or more openings 13 at a point near the lower or stove end of the chamber 10. Through this opening 13 chamber 10 opens into the atmosphere. There is a downwardly opening hood 14 bolted as at 15 to pipe section 6 above the opening 13, whereby hot air is conducted therethrough into opening 13 and chamber 10.

In a portion of conductor pipe section 6 near

the top of partition wall 7, there is rockably mounted a segmental damper 16. Damper 16 rocks on a spindle 17 having portions thereof adjacent its ends journalled in the walls of pipe section 6 and on the outer end of the spindle is a handle 18 for turning the damper. The arcuate edge of the segmental shaped damper has wiping engagement with the walls of pipe section 6 in the passage 11, while the chord side of the damper 10 is fashioned to provide a space 19 next to the partition wall 7. The damper 16 in the closed position forms a baffle across the passage 11 through which the products of combustion pass. The form of the invention shown in Figure 3 of the drawings is imperforate and is particularly adapted for stoves that utilize oil as a fuel. However, where the invention is applied to stoves burning wood and soft coal an oval shaped opening 20 is formed in the damper to the side of the 15 spindle opposed to the space 19. In all other respects the damper illustrated in Figure 5 of the drawings is constructed as heretofore described.

In lighting the stove, it will be understood that the damper 16 is turned to open position until the pipe section 6 gets hot. After the pipe section 6 is heated, the damper 16 is turned to closed position and thereafter remains normally closed. In the closed position the products of combustion from the stove are obliged to pass through space 30 19 between the peripheral edge of the damper and the partition wall, thereby forcing the products of combustion through the restricted orifice. The retardation of the products of combustion in passage 11 below the damper, prevents the escape of 35 excessive heat into the chimney, promotes maximum heating efficiency in the stove, and intensifies the heat in air chamber 10. Air from the atmosphere entering the opening 13 is heated and rises in the chamber 10 and passes out of the open 40 end 12 into the conductor pipe C. The flow of air through the hot chamber 10 creates a pull or suction through the space 19, and this suction pulls all of the heavy fumes into the chimney before they have an opportunity to condense and 45 collect on the side walls of the conductor pipe.

Having thus described the invention, what is claimed as new is:—

1. A deposit eliminator comprising a conductor pipe to convey products of combustion from a 50 stove to a chimney, a longitudinally extending partition in a portion of the conductor pipe dividing the interior thereof into a passage for the products of combustion and an air chamber, said air chamber closed at the end toward the stove 55 and opening into the passage at the end toward the chimney, a normally closed damper mounted in the conductor pipe and fashioned to provide a space between its periphery and the partition so as to cause increased flow of the products of 60 combustion next to the partition wall, and said conductor pipe formed with an opening leading into the chamber from the atmosphere near the closed end thereof whereby air is admitted to the lower end of the chamber where it is heated and 65 passed out of the chamber into the conductor pipe above the passage creating a suction to withdraw heavy fumes from the passage and prevent condensation in the conductor pipe.

2. A deposit eliminator comprising a conductor pipe to convey products of combustion from a stove to a chimney, a longitudinally extending partition in a portion of the conductor pipe dividing the interior thereof into a passage for the 5 products of combustion and an air chamber, said air chamber closed at the end toward the stove and opening into the passage at the end toward the chimney, a normally closed damper mounted in the conductor pipe and fashioned to provide a space between its periphery and the partition 10 so as to cause increased flow of the products of combustion next to the partition wall, said conductor pipe formed with an opening leading into the chamber from the atmosphere near the closed end thereof whereby air is admitted to the lower 15 end of the chamber where it is heated and passed out of the chamber into the conductor pipe above the passage creating a suction to withdraw heavy fumes from the passage and prevent condensation in the conductor pipe, and a hood secured to the outside of the conductor pipe about the opening.

3. A deposit eliminator comprising a conductor pipe to convey products of combustion from a 25 stove to a chimney, a longitudinally extending partition in a portion of the conductor pipe dividing the interior thereof into a passage for the products of combustion and an air chamber, said air chamber closed at the end toward the stove 30 and opening into the passage at the end toward the chimney, a normally closed imperforate damper mounted in the conductor pipe and fashioned to provide a space between its periphery and the partition so as to cause increased flow 35 of the products of combustion next to the partition wall, and said conductor pipe formed with an opening leading into the chamber from the atmosphere near the closed end thereof whereby air is admitted to the lower end of the chamber 40 where it is heated and passed out of the chamber into the conductor pipe above the passage creating a suction to withdraw heavy fumes from the passage and prevent condensation in the conductor pipe.

4. A deposit eliminator comprising a conductor pipe to convey products of combustion from a stove to a chimney, a longitudinally extending partition in a portion of the conductor pipe dividing the interior thereof into a passage for the 50 products of combustion and an air chamber, said air chamber closed at the end toward the stove and opening into the passage at the end toward the chimney, a normally closed apertured damper mounted in the conductor pipe and fashioned to 55 provide a space between its periphery and the partition so as to cause increased flow of the products of combustion next to the partition wall, and said conductor pipe formed with an opening leading into the chamber from the atmosphere near the closed end thereof whereby air is admitted to the lower end of the chamber where it is heated and passed out of the chamber into the conductor pipe above the passage creating a suction to withdraw heavy fumes from the passage and prevent 60 condensation in the conductor pipe.

JOSEPH AUDETTE.
